UNITED STATES PATENT OFFICE.

LOUIS HENRY GERDING, OF BALTIMORE, MARYLAND, ASSIGNOR, BY MESNE ASSIGNMENTS, TO THE TOBACCO STEMMING MACHINE COMPANY.

TOBACCO-STEMMING MACHINE

1,107,056.

Specification of Letters Patent. Patented Aug. 11, 1914.

Application filed November 14, 1910. Serial No. 592,392.

To all whom it may concern:

Be it known that I, LOUIS HENRY GERDING, a citizen of the United States, and resident of Baltimore, in the State of Maryland, have invented certain new and useful Improvements in Tobacco-Stemming Machines, of which the following is a specification.

This invention relates to machines for removing stems from tobacco leaves and particularly to that class of such machines of which an example is found in U. S. Letters Patent No. 888,835, issued May 26th, 1908, in the name of John O. Morris, and in which strippers for holding back the blades of the leaf and tearing them from the advancing stems, are covered with card teeth, and are held without advancement while the stripping action is taking place. The present invention retains the principle of utilizing card teeth as a barrier for the blades of the leaf while the stem is drawn through but utilizes a novel disposition of the card members.

In the accompanying drawings: Figure 1 is a side view of a machine embodying my invention. Fig. 2 is a view of the stripping rolls. Fig. 3 is a sectional view taken longitudinally of the stripping rolls with associated mechanism partly in elevation and partly in section. Fig. 4 is a detail view of the guides for the carrier chains of the gripper jaws. Fig. 5 is a side view of the gripper jaws. Fig. 6 is a detail view of means for rotating the stripper rolls.

The stripper rolls 2 are covered with card teeth 4 as shown in Fig. 2, and to them the tobacco leaves are presented by gripper bars 1 on upper and lower pairs of carrier chains 10 which, as well known, pass around sprocket wheels and are driven to cause the gripper bars to move in a direction from right to left of Fig. 2, to thus draw the stems between the stripping elements. The blade of the leaf in the stripping action collects in front of the stripping rolls, as shown at 3, while the stem is carried on by the gripper bars.

The stripping rolls are controlled so that they will have no tearing action on the blade of the leaf, such as would result from rotating the stripping elements rapidly as the leaf is presented to them and the stem is being drawn between them. They are given a slow rotation in a direction opposite to

the drawing in movement of the gripper bars so that they will be constantly acting to clear themselves of the accumulated leaf. By this, instead of bunching up the leaf against the deflected card teeth and thereby tearing the stem from it, the collected blade is continuously rolled out and back so as to develop a better stripping action of the teeth along the sides of the stems instead of a tearing action, due to drawing the stems through the collected bunch of blade. Among the practical advantages arising from this slow clearing action during the time of actual stemming, is the avoidance of strain on the stem due to the compacting of the bunch of blade about it and thus liability of breaking of the stem is avoided during this period. In addition to this slow rotation of the stripping rolls, they are given a quick rotation to clear or throw out the accumulated blade or bunch and present a new section of the card teeth in position to do the next stripping. This quick rotation is given in the same direction that the slow motion takes place, viz: backward in respect to the drawing-through movement of the gripper bars, as shown in Fig. 2 by the arrows.

The continuous slow movement is given to the stripping rolls by belts 48 passing around pulleys 43 on the shafts of the stripping rolls, these belts being driven by the pulley 13^a, which is driven through a chain 42 and sprocket wheels, one on the shaft of the sprocket about which the lower carrier chain passes, this shaft being driven through chain 38 and sprockets 39-40.

The quick or clearing rotation of the stripping rolls or elements which follows the slow stripping rotation is given by ratchet wheels 6, fixed on the shafts 5 of the stripping rolls, pawls 7 pivoted to loose gears 8 engage these ratchets and rack bars 9 engage the gears. These rack bars are operated by a lever 11 pivotally mounted at 11^a on the frame and having an arm 11^b with a cam shaped end 11^c to be depressed by cam blocks 34^b on the lower gripper bar carrier chain. This quick movement of the rolls is in the same direction as the slow movement, being indicated by the arrows in Fig. 2, for clearing the rolls of the accumulated blade and for bringing a new section of the roll into play for performing the stripping. When this quick clearing action occurs the

belts 48 simply slip in the pulleys 43^a. The stripping rolls are pressed together by springs 44 and they are separated to permit the passage of the gripper bars by the cam blocks 34^b on the upper and lower carrier chains of the gripper bars, which cam blocks act upon rollers or disks 5^a on the shafts of the stripper rolls. The gripper bars shown in Fig. 5 are normally of curved form from 10 end to end, diverging from each other from their center portions to their ends. They are flexible and, being held together by their carrier chains 34 running between the guide rails 34^a of the frame, they are adapted to 15 hold a series of stems between them, notwithstanding the fact that said stems may be of different thicknesses. It will thus be seen that the guides 34 not only serve to cause the chains to be properly directed but they exert 20 control over the gripper bars to make them perform their proper functions.

To satisfactorily arrest the blades of the leaf and tear them from the stems, as the stems are drawn forward by grippers 1, it is 25 necessary that a substantial portion of the body of the strippers 2 close upon the leaf 3. It is also desirable that the card clothing 30 of the strippers 2, on at least the side of approach of the leaves, be cylindrical, in order that a rotary discharging movement 35 of the strippers may be effected after each stripping action has been performed to the desired degree; said discharging or clearing action being also desirable for presenting constantly changing portions of the card 40 clothing at the stripping point. Effective stripping commences about at the time when the grippers 1 reach a point in line with the centers of the strippers, although final stripping takes place at a point considerably in 45 advance thereof. Should the radius of the cylindrical portion of the strippers be relatively large, stripping would commence too far back of the butt of leaf and there would be considerable waste, particularly if working with small leaf tobacco, such as the Cuban or some grades of northern tobacco. Accordingly, I make the diameter of the cylindrical portion of the strippers, measured 50 to the ends of the card teeth, proportional to the length of leaf to be stemmed. This feature may be embodied either in strippers composed of endless belts of card surface running around stripping rolls, or the feature 55 may be embodied and is preferably embodied in strippers comprising a pair of cylindrical card members 2, as herein shown.

I employ a suction receiver 48 and air trunk 50 and suction fan 51 for removing 60 the blades when cleared from the stripping rolls.

It will be observed that while the carriers for the gripper bars are flexible they are held by the guides in which they travel against flexing as they are presenting the gripper bars with the leaves to the stripping rolls and, notwithstanding the fact that the stripper elements have a relative separating and approaching action and in the latter action exert more or less pressure upon the gripper bars and leaves, said gripper bars are sustained in one plane to properly present and carry the leaves.

I claim:

1. In combination in a tobacco stemming machine, stripping members, means for giving said stripping members, a slow rotary movement, means for drawing the stems between the stripping members and in a direction opposite to the slow surface travel of the stripping members where they engage the leaf and stem and means for accelerating the rotary movement of the stripping elements, the slow rotation constantly clearing the blade and the accelerated movement 85 completing the clearing of the blade from the stripping means, substantially as described.

2. In combination stripper rolls, means for presenting the tobacco leaves to the rolls and for drawing the stems between the rolls, a slip-drive for the stripper rolls for 90 rotating them in opposition to the travel of the leaves, and a positive drive for giving accelerated rotary movement to the stripping 95 rolls, substantially as described.

3. In combination stripper rolls, means for presenting the tobacco leaves to the rolls and for drawing the stems between the rolls, a slip-drive for the stripper rolls for rotating them in opposition to the travel of the leaves, and a positive drive for giving accelerated rotary movement to the stripping 100 rolls, and means for automatically and periodically rendering the positive drive operative, substantially as described.

4. In combination a pair of stripper rolls, carrier means for the leaves to present them to the stripper rolls and to draw the stems between them, and driving means giving the rolls a slow continuous rotary movement and a quick rotary movement in opposition to the traveling movement of the leaves, and means for timing the said movements relative to each other.

The foregoing specification signed at Baltimore, Maryland.

LOUIS HENRY GERDING.
